INVENTOR.

BY *Victor J. Evans*

ATTORNEY

UNITED STATES PATENT OFFICE

AARON DOLGIN, OF TOLEDO, OHIO

CIRCUIT CLOSER

Application filed October 24, 1928. Serial No. 314,761.

This invention relates to improvements in circuit closers and has for an object the provision of a time controlled circuit closer by means of which a circuit may be opened and closed at predetermined periods, the invention being especially adapted for use as an automobile accessory to control the parking light.

More specifically stated, the invention provides a time controlled switch which may be set to close a circuit through the parking lamp of an automobile at a predetermined hour, so that the lamp will be illuminated for a given period and will thereafter be automatically extinguished.

With the above and other objects in view, the invention further includes the following novel features and details of construction, to be hereinafter more fully described, illustrated in the accompanying drawings and pointed out in the appended claim.

In the drawings:—

Figure 1 is a front elevation of the invention with a portion broken away to more clearly illustrate the same.

Figure 2 is a diametrical section.

Referring to the drawings in detail wherein like characters of reference denote corresponding parts, the reference character 10 indicates a housing which is adapted to enclose the switch mechanism and a time mechanism, the latter being of the ordinary character and therefore not illustrated in full. This time mechanism includes a minute hand 11 and an hour hand 12 which travels around a dial 13 and these hands are enclosed between this dial and a lens 14 which is carried by a frame or ring 15, the latter being mounted for rotation.

Mounted within the housing is a post 16 having means 17 at one end for permanent connection in an electric circuit, a portion of one of the conductors of the circuit being indicated at 18. Pivotaly mounted upon the post 16 as shown at 19 is a switch arm 20 and one end of this switch arm is adapted to engage a contact 21 to which is connected a conductor 22. The switch arm 20 is yieldingly held engaged with the contact 21 by means of a spring 23.

Mounted upon an arbor 24 of the time mechanism is a rotatable and slidble gear 25 which is engaged and driven by a pinion 26 operated by the time mechanism referred to. Independently rotatable upon the arbor 24 is a cam 27 which is carried by a sleeve 28 and secured to this sleeve is an indicator or pointer 29. The cam 27 includes a high portion 30 and a low portion 31 which are adapted to be engaged by a finger 32 which extends from the gear 25. This gear is engaged by a spring arm 33 which has one end anchored as at 34 while its opposite end 35 is adapted to engage an extension 36 of the switch arm 20.

When the finger 32 which is rotated by the gear 25 travels over the high portion 30 of the cam 27, the spring arm 33 will be pressed inward so as to move the switch arm 20 against the action of the spring 21 to open the circuit so that the parking light or other electric element connected in the circuit will be extinguished. However, when the finger 32 rides upon the low portion 31 of the cam 27 the switch arm 20 will be moved pivotally to open the circuit.

Assuming that the finger 32 is engaged upon the high portion of the cam and the circuit is open, in order to set the switch the indicator arm 29 is moved to the hour on the dial 13 at which the lamp is to be lighted. This movement of the indicator arm 29 is accomplished by means of a finger 37 which is carried by the frame or ring 15. The cam 27 will then be positioned so that the finger 32 will ride over the low part of the cam and permit the spring 23 to close the switch when the desired hour is reached. The finger 32 will ride over this low portion of the cam 27 and the circuit will remain closed during this time. However, when the finger 32 reaches the high portion of the cam the spring arm 33 will be depressed and the switch arm 20 actuated to open the circuit.

By positioning the indicator arm 29 one-half or one-quarter hour between the hours marked on the dial 13, divisions of the hour may be obtained and the switch operated at these periods.

The invention is susceptible of various

changes in its form, proportions and minor details of construction and the right is herein reserved to make such changes as properly fall within the scope of the appended claim.

5 Having described the invention what is claimed is:—

In a time controlled circuit closer, a housing having a rotatable frame and a lens carried by the frame to close the front of the housing, a pivotally mounted switch arm having permanent means for connection in an electric circuit, a contact connected in said circuit, spring means to yieldingly hold the arm engaged with the contact to close the circuit, a time controlled slidingly mounted gear, spring means located in the path of sliding movement of the gear to engage the switch arm and move the latter to open position, a rotatable cam, means carried by the gear to engage the cam to control the sliding position of the gear, a pointer located adjacent the lens and fast with the rotatable cam, and a finger carried by the frame to engage the pointer and regulate the rotary position 25 of the cam when the frame is manually rotated.

In testimony whereof I affix my signature.

AARON DOLGIN.
